UNITED STATES PATENT OFFICE

GEORGE B. ASHWORTH, OF AMSTERDAM, NEW YORK

GRATE SUPPORT

Application filed June 26, 1928. Serial No. 288,316.

This invention relates, generally, to means for supporting furnace grate bars, and particularly to supports for the grates of locomotive boiler fireboxes. The object of the invention is to provide a simple and inexpensive structure of such character, which will be readily applicable in fireboxes of present standard type, and which, in service, will be unaffected by distortion of the firebox and will make air tight joints therewith.

The improvement claimed is hereinafter fully set forth.

In the accompanying drawings: Figure 1 is a vertical longitudinal section, on the line *a a* of Fig. 2, through a grate support embodying the invention, applied in a locomotive firebox; Fig. 2, a half plan or top view thereof, with the firebox in section on the line *b b* of Fig. 1; Fig. 3, a vertical transverse section, on the line *c c* of Fig. 1; Fig. 4, a similar section, on an enlarged scale, on the line *d d* of Fig. 2, and; Fig. 5, a similar section, on the line *e e* of Fig. 2.

In the practice of the invention referring descriptively to the specific embodiment thereof which is herein exemplified, and to its application in a locomotive firebox, the composite members of the grate support are comprehended in an integral structure, which is cast in metal, the heat resisting qualities of which are such as to reduce to a minimum the tendency to distort and cramp the grate bars. The grate support, 2, is a quadrilateral frame, conforming, in plan view, to the firebox, 1, in which it is applied, the water legs of said firebox being closed, at bottom, by a mud ring, 1a, in the ordinary manner. The front and rear members of the support are connected by an integral centre member, 2a.

The grate resting upon the support, may be of any suitable and preferred character, and in this instance is shown as of the rocking type and comprising a plurality of slats or flat bars, 3. Means for suspending the grate upon the support, 2, are formed thereon, these being, for the rocking grate shown, a plurality of trunnions, 2b, upon which the grates may be rocked by a shaker, in the usual manner. The entire grate support structure, 2,

is attached to the mud ring, through lugs, 2c, depending from the side members and projecting outwardly therefrom, below the mud ring, to which they are secured by studs, 2d, tapped into it. The lugs, 2c, also serve for the attachment of the side sheets of the ash pan.

For the purpose of ensuring air tight closure between the side and end members of the support or grate frame and the inside sheets of the firebox, sealing plate strips, 4, are laid on the tops of the side and end members of the support, with one of their edges contacting with the firebox sheets, and are welded or otherwise secured in place, on the frame. It is well known in locomotive practice the drafts of cool air leaking in from the margins of the grate produce undesirable contraction of the areas of the inner fire box sheets subjected to such drafts, hastening the breaking down of such sheets. Where the grate frame is set in place as a unit, it is impossible to make a snug fit with the fire box sheets due to the irregular contour of the sheets, and of the grate frame itself. If the frame is moved to one side to close the gap, it will open a wider gap on the other side. Where separate cast side bars are used for supporting the grate bars difficult chipping operation must be resorted to, to insure a proper fit. The present invention enables a snug fit to be made by merely adjusting the thin sealing strips 4, into proper engagement with the inner sheet after the grate frame has been installed and welding them in place. The invention therefore, provides a commercial and convenient means of effectively closing gaps between the frame and the inner sheet.

In the integral support structure above described, the side and centre members are fixedly spaced apart by the end members, thereby providing and maintaining a predetermined clearance for the rocking of the grate bars, an advantage not presented in the ordinary construction, in which the side and centre members are separately applied, with the result of allowing movement of one relatively to another, on account of warpage, or distortion of the fire-box due to pressure or

heat. Such movement occurs to the extent that the grate bars become cramped and prevented from rocking, or, if sufficient force is applied, will be displaced.

5 It is, further, in the application of the invention, possible to assemble all the grate bars in the support, before locating it in the firebox, which attains the advantage of checking the grate bar clearance much more conveniently than if all the parts were installed 10 in operative position in the firebox. A further advantage is the elimination of the front and rear brackets necessary to position the centre member in present practice. If the firebox should be of such width as to require 15 more than the two parallel rows of rocking grate bars herein shown, the invention is equally well adapted to the condition, as additional centre support members, spaced and 20 joined in the integral structure by the end members, will only be required.

The invention claimed and desired to be secured by Letters Patent is:

1. In a locomotive, the combination of a 25 steam boiler firebox having inner and outer sheets; a grate support structure therein, comprising side and end members disposed within the walls of the boiler and connected to same for support; and separately formed sealing plates, located on the tops of the side and 30 end members, and contacting with the adjoining firebox sheet.

2. In a locomotive, the combination of a 35 steam boiler; a grate support structure, comprising side and end members attachable as a unit within the walls of the boiler and connected to same for support; and a plurality of separately formed sealing plates disposed on the members and contacting with the adjoining boiler wall.

3. In a locomotive, the combination of a 45 steam boiler; a grate support structure attachable as a unit within the walls of the boiler and connected to same for support, comprising side and center members spaced apart and connected by end members; and separately formed sealing plates located on the tops of the side and end members, and contacting with the adjoining boiler wall.

4. In a locomotive, the combination of a 50 steam boiler; a grate support structure attachable as a unit within the walls of the boiler and connected to same for support, comprising side and end members; and separately formed sealing plates located on the tops of the side and end members, and contacting with the adjoining boiler wall, and 55 welded in place.

5. In a locomotive, the combination of a 60 steam boiler; a grate support structure attachable as a unit within the walls of the boiler and connected to same for support, comprising side and end members; separately formed sealing plates disposed on the members 65 and contacting with the adjoining boiler

wall and supporting brackets projecting horizontally from the structure and secured to the bottom of the boiler, adapting the structure to be inserted as a unit from the bottom of the boiler.

6. In a locomotive, a firebox having a sheet metal inner wall; a unitary grate support loosely fitting within the fire box providing spaces therebetween; means for rigidly securing the grate support detachably to the fire box extending beneath the grate support; and sheet metal sealing plates spanning the spaces between the grate support with the interior walls of the fire box.

7. In a locomotive, a fire box having a sheet metal inner wall; a unitary grate support loosely fitting within the fire box providing spaces therebetween; means for rigidly securing the grate support detachably to the fire box extending beneath the grate support; and sheet metal hermetically-sealed sealing plates spanning the spaces between the grate support with the interior walls of the fire box.
